Inventor
Samuel F. Allen

UNITED STATES PATENT OFFICE.

SAMUEL F. ALLEN, OF CHICAGO, ILLINOIS.

IMPROVED WATER-HEATER FOR LOCOMOTIVE-ENGINES.

Specification forming part of Letters Patent No. 29,452, dated August 7, 1860.

To all whom it may concern:

Be it known that I, SAMUEL F. ALLEN, of Chicago, in the county of Cook and State of Illinois, have invented certain new and useful Improvements in Feed-Water Heaters for Locomotive-Engines; and I do hereby declare that the following is a full, clear, and exact description of the same, reference being had to the accompanying drawings, and to the letters of reference marked thereon.

The nature of my invention consists in constructing and arranging those parts which will be particularly described, substantially as set forth.

In the annexed drawings, Figure 1 is a longitudinal cross-section of the heater and the exhaust-pipes. Fig. 2 shows an end view of the boiler and side view of the heater. Fig. 3 is a view of the heater with one end removed. Fig. 4 is a view of the exhaust-pipes. Fig. 5 is a side elevation of the boiler and end view of the heater and a section of the float-valve.

In the figures, A represents the boiler and B the water-heater, said boiler and heater being connected together by means of the pipe A'. The heater B is provided internally with three chambers—a water-chamber b and two steam-chambers a and c'. These chambers, as seen, are annular, the water-chamber being situated between the two steam-chambers.

cccc represent a series of water-tubes which connect with the water-chamber b, passing across the inner steam-space, as clearly shown in Fig. 2.

s s s are a series of stay-tubes which connect the two steam-chambers, being made to pass through the water-chamber.

D D represent the exhaust-pipes, which are constructed in the manner represented, each pipe being divided and having two steam-outlets. Two branches of these pipes unite, as seen, and enter the heater B, conveying a portion of the exhaust-steam into the outer steam-chamber a.

m represents a pipe which connects the water-chamber in the heater with the valve-case H. In this valve-case is a valve I, which is so constructed as to float when the case is

filled with water, so that unless the case is almost empty the valve is out of its seat, and thus water may pass through. This valve-case connects with the force-pumps of the engine and the pumps connect by a pipe to the pipe B'. (Seen in Figs. 2 and 5.)

The exhaust-steam from the engine passes through the exhaust-pipes D D and a portion of it enters the heater, as represented in Fig. 1. The water-chamber b being filled with water, it will be seen that as the steam surrounds the said water-chamber it will be condensed, and when condensed it will pass out through the pipe m into the valve-case H and thence through the pumps, and will be returned from the pumps to the heater, entering the water-chamber through the pipe B'. The pressure caused by the pumps forces the water from the heater or water-chamber into the boilers through pipe A'. It will be seen that by this arrangement of the heater surrounded by steam and with steam on its inside the water within the heater will always be kept warm to be injected into the boilers. When the water leaves the valve-case H, so that the valve will not float, said valve sinks into its seat and prevents any escape of steam, as will be readily seen. It also prevents the entrance of impurities into the pumps.

Having thus fully described my invention, what I claim as new, and desire to secure by Letters Patent, is—

1. The employment of the heater constructed, in the manner represented, with steam-chambers a and c and intervening water-chamber b, said chambers being connected substantially in the manner and for the purpose specified.

2. In combination with the heater B, the compound exhaust-pipes D D, when the same are arranged and used substantially as and for the purpose herein specified.

3. In combination, the float-valve V, substantially as and for the purpose specified.

SAML. F. ALLEN.
